Carpets

No. 11,513

Nov 18, 1879

UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR CARPET-BORDER.

Specification forming part of Design No. **11,513**, dated November 18, 1879; application filed September 20, 1879.
[Term of patent 3½ years.]

To all whom it may concern:

Be it known that I, CHARLES MAGEE, of Brooklyn, in the county of Kings and State of New York, have invented a new and original Design for the Border of a Carpet, of which the following is a specification.

This invention relates to a new and original design for the border of a carpet.

The invention is illustrated in the accompanying photograph, which represents a face view of a border provided with my newly-invented design.

Upon the border are represented a series of lyre-shaped ornaments, A A, each ornament A being formed of two S-shaped scrolls, a a, and surmounted by a crown-piece, b, as shown. Below each ornament A are two small geometrical figures, d e. Between the several ornaments A A are represented floral groups f f. The border is, by two stripes, g h, divided into three parallel fields, i j, and k. The stripes g h and the fields i j k do not, however, traverse the ornaments A.

Within the field i are situated the floral groups f. Within the field j are fantastical

floral top pieces, l, which begin at the stripe g and terminate in the field k.

I claim—

1. The design for the border of a carpet, consisting of the lyre-shaped ornaments A A, substantially as shown.
2. The design for the border of a carpet, consisting of the ornaments A, crown-piece b, and figures d e, substantially as shown.
3. The design for the border of a carpet, consisting of the ornaments A and floral groups f, substantially as shown.
4. The design for the border of a carpet, consisting of the ornament A and stripes g h, which stripes terminate at said ornament, substantially as shown.
5. The design for the border of a carpet, consisting of the ornaments A, stripes g h, forming fields i j k, and of the groups f and floral top pieces, l, substantially as shown.

CHARLES MAGEE.
